UNITED STATES PATENT OFFICE.

HIRAM B. SPRAGUE, OF LEAVENWORTH, KANSAS.

FURNACE-DOOR-OPERATING DEVICE.

SPECIFICATION forming part of Letters Patent No. 588,025, dated August 10, 1897.

Application filed February 19, 1897. Serial No. 624,101. (No model.)

To all whom it may concern:

Be it known that I, HIRAM B. SPRAGUE, of Leavenworth, Leavenworth county, Kansas, have invented certain new and useful Improvements in Locomotive-Furnace-Door-Operating Devices, of which the following is a full, clear, and exact description, reference being had to the accompanying drawings, forming a part thereof.

10 My invention relates to locomotive-furnace-door-operating devices; and my object is to produce a device of this character which is reliable in operation and simple, strong, durable, and inexpensive of construction.

15 The invention consists in certain novel and peculiar features of construction and organization, as hereinafter described and claimed.

20 In order that the invention may be fully understood, reference is to be had to the said accompanying drawings, in which—

25 Figure 1 represents a vertical section of a locomotive-cab and illustrates in rear elevation the furnace-door and its operating devices. Fig. 2 represents a horizontal section taken on the line II II of Fig. 1, showing the floor of the cab partly broken away. Fig. 3 represents a vertical section taken on the line III III, Fig. 1.

30 Referring to the drawings in detail, 1 designates the cab of a locomotive.

35 2 designates the rear end or side of a furnace and boiler, and 3 the door-opening thereof, through which fuel is introduced into the furnace. At one side of said door-opening is arranged a hinge-rod 4, it being journaled in the bearing-brackets 5, two of them below and one above, preferably, the floor of the cab. One of the upper brackets is formed with an upper cam or inclined surface 6.

40 7 designates the furnace-door, which closes the opening 3 and is provided with hinge-arms 8, which embrace the hinge-rod 4, and are secured rigidly thereon by means of the set-screws 9 or in any equivalent manner.

45 One of said arms is provided with a lower inclined or cam-face 10, which conforms to and rests upon the upper inclined face of the bracket 5, hereinbefore referred to. By this arrangement it is obvious that when the rod 4 is rotatably operated in the proper direction the cam-surface 10, resting upon the cam-surface 6, causes the door and hinge-rod to

be elevated bodily a slight distance, and when open to assume approximately the position illustrated in dotted lines, Fig. 1, so 55 that when the power is removed which opens the door and holds it open the door by gravity will swing back to its original or closed position, the cam-surface 10 of the arm 8 sliding down upon the cam-surface 6 of the 60 bearing-bracket 5. Thus it will be seen that the door cannot be accidentally left open and permit cold air to enter and chill, or, rather, reduce the temperature of the furnace, and thereby necessitate a greater consumption 65 of fuel.

11 designates a plate secured to the door 7 and provided with a curved arm 12, terminating in an enlargement, and a pin 13.

At a suitable point, on the furnace-wall, 70 by preference, is a ring 14, and fitting therein at one end is a coil-spring 15, which tapers diametrically toward and at its opposite end surrounds and preferably engages an opening in the pin 13, so that there is no possible 75 chance of dislocating the spring by opening or closing the door forcibly or otherwise. The function of this spring is to automatically and reliably close the door and hold it closed, except when resisted by an overcom- 80 ing force or power, as hereinafter explained.

16 designates an arm which is mounted rigidly by means of the set-screw 17 or its equivalent upon the hinge-rod 4 near its lower end, and is pivotally connected at its opposite end 85 as at 18, to operate in a horizontal plane to the link 19, which link in turn is pivotally connected to a second and lower link 20, that the latter may operate in a vertical plane. Said link 20 at its opposite end is pivotally 90 connected to operate in a horizontal plane, as at 21, to the short link 22, and said short link at its opposite end is pivotally mounted between the vertical ears 23 of a lever 24, which lever is pivotally connected to operate in a 95 vertical plane to the bracket 25, bolted or otherwise rigidly secured to the bottom of the floor of the cab.

The lever 24 is provided also with a pair of upwardly-projecting ears 26, in which is pivotally mounted at 27 the lower end of the short link 28, and said link at its upper end is pivotally connected to the link 29, so that the latter may swing in a vertical plane, but

at right angles to the movement of the link 28. In order that this relation between said links may be established, the floor of the cab is provided with an opening 1^a through which 5 said links extend.

30 designates a foot-plate hinged, as at 31, to the floor of the cab and provided with a recess 32 near its opposite end, across which a pin 33 extends transversely. Pivoted, as 10 at 34, to the upper end of the link 29 in a plane at right angles to that of the latter's connection with the link 28 is a short link 35, the upper end of which is loosely mounted upon the cross-pin 33.

15 The foot-plate 30 is normally elevated and maintained in such position by the spring 15 or its equivalent, and consequently the door 7 is normally held closed with a yielding pressure, as hereinbefore explained, and such pressure assisted, as pointed out, by utilizing the 20 weight of the door to prevent it from accidental opening.

In case it may be necessary at any time to hold the door open I have provided the free 25 and upper end of the foot-plate with a tooth or shoulder 36 and have provided the dog 37, pivotally mounted on a bracket 38, to engage said foot-plate when moved properly by the operator. When it is desired to close the 30 door, all that is necessary to do is to place the foot upon the foot-plate and simultaneously depress the same slightly and force the dog out of engagement with the shoulder 36. The spring is then permitted to raise the foot- 35 plate and close the door.

In the practical operation of firing a locomotive-furnace the fireman usually has to get a shovelful of coal and hold it in one hand or rest it upon the floor of the cab until he opens 40 the furnace-door. He then throws the coal into the furnace and either closes the door or leaves it open until he gets the next shov-

ful. By the first method a great deal of time and labor are unnecessarily wasted and by the latter method an unnecessary quantity of fuel 45 must be consumed in order to counteract the influence of the chilling currents of air that enter the furnace and flues of the boiler while the door is open. With my invention the fireman gets his coal and as he steps toward the 50 furnace and upon the foot-plate the latter is depressed and the door consequently opened without loss of time or labor on the part of the fireman, who feeds the fuel to the furnace and then removes his foot from the foot-plate to permit the door to automatically and 55 reliably close and steps back for the next shovelful of coal.

Having thus described the invention, what I claim as new, and desire to secure by Letters 60 Patent, is—

In a furnace-door-operating device, the combination of a vertical hinge-rod suitably supported adjacent to the door-opening, a door mounted thereon, a curved arm projecting 65 from said door and terminating in an enlargement or shoulder and a pin, a ring or annulus secured to the furnace, a spiral spring seated at one end in said ring or annulus and embracing at its opposite end the pin of the door-arm, 70 an arm mounted rigidly on said rod below the floor of the cab, a link-rod, a pair of short links connecting said rod with said lever and with said arm, a foot-plate hinged to the upper side of the floor, a link-rod, and a pair of 75 short links connecting said rod with the foot-plate and the lever below the floor of the cab, substantially as described.

In testimony whereof I affix my signature in the presence of two witnesses.

HIRAM B. SPRAGUE.
